CLAIM

The ornamental design for a light fixture lens with alternate geometric overlay features, as shown and described.

DESCRIPTION

FIG. 1 is a perspective view of the first embodiment with a central overlay feature and outer overlay feature.

FIG. 2 is a perspective view of the second embodiment with a central overlay feature and no outer overlay feature; and, FIG. 3 is a perspective view of the third embodiment with a central overlay feature and four corner overlay features.

The broken lines shown in FIG. 1 through FIG. 3 depict environmental subject matter only, and form no part of the claimed design.
